UNITED STATES PATENT OFFICE.

JAMES B. MCQUEEN, OF PRESTON, IDAHO.

HOIST.

Application filed April 11, 1921. Serial No. 460,331.

To all whom it may concern:

Be it known that I, JAMES B. MCQUEEN, a citizen of the United States, residing at Preston, in the county of Franklin and State of Idaho, have invented certain new and useful Improvements in Hoists, of which the following is a specification.

This invention relates to improvements in hoisting mechanisms.

10 The primary object of this invention is the provision of an improved hoisting mechanism which may be used in connection with the elevation and lowering of hoists for the efficient performance of such duty, receiving 15 the driving power therefor from a prime mover which may be also used for operating other mechanisms, such as a concrete mixer; the hoisting mechanism being particularly designed so that it may be moved into driving 20 relation with the prime mover as desired.

Other objects and advantages of this invention will be apparent during the course of the following detailed description.

In the accompanying drawings, forming 25 a part of this specification, and wherein similar reference characters designate corresponding parts throughout the several views.

Figure 1 is a side elevation of the improved hoisting mechanism, showing the prime mover therefor, and the transmission mechanism for connecting the same for operation by the prime mover.

Fig. 2 is a cross sectional view taken substantially on the line 2—2 of Figure 3.

Fig. 3 is a plan view of the improved hoisting mechanism.

Fig. 4 is a cross sectional view taken substantially on the line 4—4 of Figure 3.

40 Fig. 5 is an end elevation of a bracket construction which may be used in connection with the movable mounting of a drum supporting shaft used in this invention.

Referring to the drawings in detail, 45 wherein for the purpose of illustration is shown but the preferred embodiment of this invention, the letter A may generally designate the improved hoisting mechanism which may be connected by means of a transmission mechanism E to a prime mover C, so that the prime mover C may be selectively used for driving the hoisting mechanism A or any other suitable mechanism, such as a concrete mixer D.

55 The transmission mechanism E includes a substantially rectangular frame 19 which

includes a pair of longitudinally extending side beams 20 connected together by the upstanding substantially inverted U-shaped brackets 21, which extend transversely across the frame 19. The upper terminals of the brackets 21 carry suitable bearings 22, in which is rotatably mounted the driven shaft 23. The lower terminals of the brackets 21 are provided with attaching feet 24, which form means whereby the brackets 21 may be readily bolted or otherwise secured to the longitudinally extending side beams 20. The bracket 21 nearest to the prime mover C, at its outer face, is provided with a bearing 25, in which is rotatably mounted the crank shaft 14. The outer end of the crank shaft 14 has keyed or otherwise secured thereto a sprocket wheel 26, which is in the same plane with the relatively large sprocket 75 wheel 27 carried by shaft 23, and a drive sprocket chain 28 is trained around these sprocket wheels. The bracket 21 farthest from the prime mover C has its outer face provided with a bearing 29, which is mounted in a plane below the bearing 25 and rotatably supports the counter shaft 30, which has keyed or otherwise secured thereto a sprocket wheel 31, which is in the same plane with a sprocket wheel 32 keyed to the drive 80 shaft 23. These sprocket wheels 31 and 32 have trained around the same a drive sprocket chain 33. The inner end of the shaft 30 is provided with a relatively large friction disc or drive wheel 34, the purpose of which will be hereinafter more fully described.

The hoisting device A includes a pair of relatively small brackets 35 and 36, which are bolted to the upper surfaces of the longitudinally extending beams 20, and which are arranged intermediate the relatively large inverted U-shaped brackets 21. The bracket 35 has a guide 37 bolted upon the upper surface of the bracket and provides a slot 38 adapted for alignment with a slot 38^a in the bracket 35 to receive the pivot bolt 39 which extends through the inner end of a shaft 40. The end of the shaft is squared, as clearly shown in Figure 5 of the drawings. The aligning slots 38^a and 38 provide means whereby the shaft 40 may be adjusted, so as to allow for the adjustment of the direction of pull, so that the rope will always roll evenly upon the drum 41. The drum 41 is rotatably mounted upon the opposite end of the shaft 40 from the bracket

35, and this end of the shaft extends beyond the bracket 36. The bracket 36 is also provided with a guide 42 in which is slidably mounted the shaft 40, to permit the 5 shaft to swing in an arc at this point. The drum 41 may be of the ordinary construction and has applied to the inner end thereof the friction disc or driven wheel 43. The outer surface of this friction disc may be 10 provided with rubber, fiber, or the like, and is adapted to be moved into and out of engagement with the friction disc 34 so as to permit the rotation of the drum 41.

A hand lever 44 is provided for swinging 15 the shaft 40 on its pivot bolt 39, for moving the friction disc 43 into and out of engagement with the friction disc 34, and the lower end of the hand lever is pivotally connected, as at 45, to a bracket 46. The extreme lower 20 end of the hand lever 44 has pivotally connected thereto an operating link 48 which has its opposite end pivotally connected to an adjusting lever 49. The adjusting lever 49 is pivotally secured adjacent to its upper 25 end on a pivot pin 50 which is adapted to be inserted in any one of a plurality of apertures 51 formed in a supporting portion 52 of the bracket 36 and in this manner, the position of shaft 40 may be located according to the size of disc 43. The upper 30 end of the adjusting lever 49, above the pivot pin 50, is forked, as at 53, and receives the shaft 40. One of the longitudinally extending beams 20 is provided with an 35 auxiliary frame 55 which supports a brake shoe 56. The brake shoe 56 is provided with an attaching foot 57 whereby the same is secured to the auxiliary frame 55, and an arcuate body which conforms to the curvature of the friction disc 43. A relatively strong coil spring 58 is secured to the lever 49 adjacent to its lower end and to one of the beams 20 and normally tends to move the shaft in the direction of the brake shoe 45 56, so that the friction disc 43 will engage the shaft and thus prevent accidental rotation thereof.

The transmission mechanism may be connected as by means 62 for operating other 50 mechanism, such as a concrete mixer D. The counter shaft 30 will be operated through the medium of the sprocket wheels 32 and 31, and the sprocket chain 33, and when it is desired to rotate the drum 41 the 55 hand lever 44 is shifted so that the friction disc 43 will be moved into engagement with the friction disc 34, which will effectively rotate the drum 41. When it is desired to hold the drum 41 at any desired point it is 60 merely necessary to release the lever and the relatively strong contractile spring 58 will

move the friction disc 43 into engagement with the brake shoe 56. The speed of rotation of drum 41 may be regulated by bearing lightly on the lever or by bearing hard 65 on the lever or the speed of rotation of the prime mover itself may be adjusted.

From the foregoing description it can be seen that an improved hoisting attachment is provided which is exceptionally simple 70 and durable in construction and which can be readily operated by the ordinary skilled mechanic.

Changes in details may be made without departing from the spirit or scope of the 75 invention; but,

I claim:

1. A hoisting mechanism comprising a supporting frame, a bracket carried by said supporting frame having a slot therein, a member connected to said bracket providing a slot therein in aligning relation with the slot of said bracket, a shaft having one end thereof provided with an opening therethrough, a bolt connected through said shaft opening and extending through the aligning slots of said bracket and member, a nut for clamping said bolt in a determined relation along the aligning slots whereby the shaft may be pivotally connected between the bracket and the member, a driving mechanism including a drive wheel, a drum rotatably carried by the shaft remote from its pivotal connection, a driven wheel affixed to said drum, and means for moving the shaft upon its pivot whereby the driven wheel may be moved into engagement with the drive wheel.

2. A hoisting mechanism comprising a supporting construction including a pair of 100 spaced brackets, a shaft, driving means including a drive disc, means adjustably pivoting one end of the shaft to one bracket whereby the shaft may have the pivot axis thereof moved away from or toward 105 the drive disc, the shaft remote from the bracket to which it is pivoted slidably resting upon the other bracket, operating means including a lever adjustably pivoted to the bracket on which said shaft is slidably mounted, the pivotal mounting of said lever being capable of being moved away from or toward the drive disc, said lever at an end thereof receiving the shaft in bearing relation therein whereby upon movement of the 110 lever the shaft may be pivotally moved, a drum rotatably carried by said shaft, and a wheel fixed to said drum adapted to engage or disengage the drive disc of said driving means according to the direction of movement of said shaft.

JAMES B. McQUEEN.
